UNITED STATES PATENT OFFICE

GEORGE PRENTICE CHILDERS, OF SAN FRANCISCO, CALIFORNIA

DESIGN FOR SIGN CHARACTER

Application filed February 27, 1928. Serial No. 25,598. Term of patent 3½ years.

To all whom it may concern:

Be it known that I, GEORGE PRENTICE CHILDERS, a citizen of the United States, residing at the city and county of San Francisco, State of California, have invented a new, original, and ornamental Design for Sign Character, of which the following is a specification, reference being had to the accompanying drawings, forming part thereof.

I claim:

The ornamental design for sign character, substantially as shown.

GEORGE PRENTICE CHILDERS.
